UNITED STATES PATENT OFFICE.

LEE P. HYNES, OF ALBANY, NEW YORK, ASSIGNOR TO CONSOLIDATED CAR-HEATING COMPANY, OF ALBANY, NEW YORK, A CORPORATION OF WEST VIRGINIA.

TRAIN-DOOR-CONTROL SYSTEM.

Application filed June 23, 1922. Serial No. 570,327.

For a detailed description of the present form of my invention, reference may be had to the following specification and to the accompanying drawings forming a part 5 thereof, wherein,

Fig. 1 shows the door engine used in my system;

Figs. 2, 3 and 4 are diagrams of the circuits I employ. Fig. 5 shows a modification.

My invention relates to the operating of the doors on one or more cars of a train from a single control station. Heretofore, the systems used for this purpose have been extremely complicated, involving not only two train-wires for a set of doors, but a duplication thereof for the two sides of the car or train and a further duplication of the door valve magnets and hand switches. All these features taken together have necessitated an elaborate mass of wiring which is not only costly in itself but also increases the chance of a failure by short-circuiting, crossing or grounding of one or more wires, while inspection and tracing of the circuits becomes an involved undertaking. In addition, the door-shoes commonly used to arrest the closing movement of each door also increase the complexity of the wiring and require the equipping of each door with such a shoe which is a movable member that augments the cost and is subject to uncertainty of action that it is important to eliminate.

It is my purpose by the present invention to greatly simplify the system and at the same time to improve its reliability and capacity. This I accomplish by a combination which enables me to eliminate the duplicate train-wire, the duplicate valve-magnets, also the usual limit-switches and the door-shoe with its appurtenances, while retaining practically all of the desired capacity of the previous systems with a saving in cost and a gain in reliability.

Referring to the drawing, the door-engine is shown in Fig. 1. It is provided with two differential and opposed cylinders P^1 and P^2 , the latter having a piston area one-half as large as that of the former. The two pistons are connected in the usual manner by a rack geared to a door-arm R whose outer end is provided with a roller R^2 which is free to travel in a vertical slot or guide-way S^2 on the rear edge of the door S. The door-arm R is formed in two parts con-

nected by a rule-joint b^1 that will permit the arm to bend or buckle during the door-closing movement, unless prevented by the stiffness of a spring T which normally spreads apart the two halves of the arm by 60 pressing against the lugs e , e thereon. In the event of the door being obstructed in closing, the spring T will yield and break a circuit containing the magnet-controlling switch E, the two contacts of which are 65 mounted on the respective lugs e , e aforesaid. Its action will be described hereinafter. Preferably also the arm E^1 is provided with the customary spring telescoping joint R^3 . The door engine above described 70 may be controlled for both directions of movement by a single valve which puts the large cylinder P^1 in communication with either the admission port f^2 or the exhaust port f^1 according as the valve-magnet F is 75 de-energized or energized. In the former case the admitted air pressure acting on the larger piston of P^1 will overcome the force of the smaller piston of P^2 , which is permanently connected to the air supply by the 80 pipe p^2 , and thereby opens the door. In the latter case, the cylinder P^1 being open to the atmosphere, the smaller piston will act in the opposite direction to close the door.

The circuit-diagram of Fig. 2 shows a 85 single train-line extending through three cars of a train, the inter-car connections or jumpers between successive cars being indicated by the curved loops. In this figure it is assumed that the main entrance doors are 90 at the ends of a car and the control stations are hence at the same points, an operator standing at the meeting of two platforms and working the doors on the two adjacent cars in a well known manner. In the case 95 of center-door cars the same control stations will be located at the centers of the cars, as indicated in Fig. 4. The operator's control device includes the customary battery switch G of the lock type wherein the switch stands 100 normally open to disconnect the battery, but may be unlocked and the battery connected when the controller is to be used. When its use is ended, the key which has unlocked it can then be removed only after the switch is 105 turned back to its normal, battery-disconnecting position. In addition to battery switch G, there is a circuit-closing switch at each station, by which the doorman connects to battery the train wire K, or any other 110

door-magnet circuit which is to be operated. This switch will remain closed till positively opened. Two of such circuit-closing switches are indicated at B and C in Fig. 2, the similar switches to the right of this point being marked C¹, C¹, etc., and those to the left being marked B¹. Whenever there is a door, its valve-magnet F is connected to the train-wire K by a connection which includes the aforesaid switch E. Assuming that the switches B and C are to be used and their battery connection being closed at switches G, G, and the train-line K broken at A by opening the jumper, (remaining closed at D, D) then the closure of switch B will energize the train-wire to the left of the station and the closure of switch C will energize it to the right thereof. Such energizing of the train-wire also energizes the magnets F which are connected thereto, and, referring again to Fig. 1, the admission port f² of door-opening cylinder P¹, which port has been closed by a spring f³, will be forced open and its exhaust port f¹ closed. Thereupon the air-pressure acting on the larger piston will overcome the same pressure acting on the smaller one and move it to the right, driving the air in cylinder P² back into the supply pipe p². The engine will thus rotate its door-arm R in an anti-clockwise direction and open the door controlled thereby. In this operation the door-arm is prevented from buckling by the rule-joint b¹. The door will remain open so long as the control switch B or C remains closed and its valve-magnet F remains energized. To close the door the control switch is opened and thereby the valve-magnet F is de-energized. Then the spring f³ acts to open exhaust port f¹ and close supply port f² of cylinder P¹. Thereupon the permanent air pressure on the smaller piston will drive both pistons to the left, bringing door-arm down to its horizontal door-closing position shown in Fig. 1. If in this closing movement the door should hit a passenger or be otherwise obstructed, the torsion of the engine will cause the door-arm to buckle sufficiently against the force of spring T to operate switch E. That will disconnect magnet F from the train-wire at the point X and connect it to battery at the point Z (see Fig. 2) and it will thereupon act to reverse the engine, relieving the torsion on the door-arm and restoring switch E. The door will thus resume its closing movement and if the obstruction has not been removed the action of switch E will be repeated.

Fig. 3 shows the control station for a center-door car, the train-line being broken by a switch corresponding to the jumper break in Fig. 2. For convenience such switch may be worked simultaneously with the battery switch G when the latter is unlocked.

The control switches B and C will, as in Fig. 1, operate the respective sections of train-wire K. Moreover, if desired, the local doors on the car may be disconnected from the train-wire and operated by a separate switch L corresponding to switches B and C. In like manner any desired group of doors may either have its separate control-switch, or be operated in common with other doors on the train-line K.

It will be manifest that the foregoing arrangement greatly simplifies the train door-systems heretofore in use, by reducing the wiring to a single train-wire for one side of a train without duplication of valve-magnets or the use of relays or door-shoes. The customary limit-switches are also unnecessary, because no current is flowing when the doors are closed and when they are open the current is necessary in order to maintain them open. There is no opportunity of prying back the door-shoe when the door is closed which makes it necessary in the ordinary system to cut off the current by a limit-switch when the door reaches its closed position. In my arrangement the reversing switch E can not be operated when the door-arm is in its horizontal position locking the door closed, while the spring telescope joint will allow the door to be opened in an emergency sufficiently to release a passenger's clothes or other objects which may be caught between the door and its jamb without starting the reversing action.

Instead of the differential engine shown in Fig. 1 and described above, I may employ an engine having cylinders of equal power and control it by means of a valve-engine of the aforesaid differential type. That modification is shown in Fig. 5, wherein suitable pistons within the differential cylinders P¹ and P² operate a double piston-valve H in place of the rack shown in Fig. 1. In the position of this piston-valve which appears in Fig. 5 the pressure from cylinder P¹ goes, by way of pipe p³, to cylinder Q¹ of an ordinary door engine and will cause the engine to close the door, the opposite cylinder P² being open to exhaust by way of pipe p⁴; cylinder P² and pipe p⁵. When, however, pressure is admitted to cylinder P² by valve magnet F, as heretofore described, it will throw the piston-valve to the left, as shown by dotted lines, and will thereby be admitted, by way of pipe p⁴ to cylinder Q² for opening the door, the opposite cylinder Q¹ being obviously opened to the exhaust.

What I claim as new and desire to secure by Letters Patent is:

1. The combination with a pneumatic door-engine of a control valve therefor, a magnet for operating said valve, and a yieldable switch interposed between the en-

- gine and the door and controlling the said magnet.
2. The combination with a pneumatic door-engine, of a valve controlling the door-closing movement of said engine, a spring-switch interposed between the engine and the door and operated by the engine in the event of obstruction of the door in closing, and an operating magnet for the said valve in a circuit controlled by said switch.
3. The combination with a pneumatic door-engine having a smaller piston constantly exposed to air-supply pressure and a larger piston intermittently exposed to said pressure, of a valve controlling the pressure on the larger piston, a yieldable switch between said engine and the door, and a magnet operating the said valve and contained in a circuit controlled by said switch.
4. The combination with a door-engine having a smaller piston constantly exposed to air-supply pressure and a larger piston intermittently exposed to said pressure, of a valve controlling the pressure on the larger piston, a spring holding said valve in a position to exhaust the pressure from the larger cylinder, a magnet acting on said valve in opposition to said spring, and a magnet-controlling switch between the engine and the door.
5. The combination with a series of door-engines each having a smaller engine
- constantly exposed to air-supply pressure and a larger piston intermittently exposed to said pressure, of a single valve for each engine controlling the pressure on the larger piston, a spring for each valve normally holding it in position to exhaust said pressure from the larger piston, a magnet for each valve acting thereon in opposition to said spring, a train-line to which said magnets are connected, a series of switches for connecting said train-line to a source of electrical supply and a magnet-controlling switch between each engine and the door which it operates.
6. The combination with a reciprocating pneumatic door-engine of a shaft rotated thereby, a radial arm between said shaft and the door, a valve-magnet controlling said engine, and a magnet-controlling switch between said shaft and the door.
7. The combination with a pneumatic door-engine of a yieldable switch between said engine and the door and responding to the door-closing force of said engine, a valve controlling the door-opening action of the motor and a magnet for said valve controlled by said switch.

Signed at Albany, county of Albany and State of New York, this 21st day of June, 1922.

LEE P. HYNES.
